SPRINKLER NOZZLE

Filed May 29, 1930

Louis A. Phillips
Inventor
By his Attorney
Andrew Sulz Jr.

UNITED STATES PATENT OFFICE

LOUIS A. PHILLIPS, OF DOBBS FERRY, NEW YORK, ASSIGNOR TO THE COOLING TOWER CO. INC., OF NEW YORK, N. Y., A CORPORATION OF NEW YORK

DESIGN FOR A SPRINKLER NOZZLE

Application filed May 29, 1930. Serial No. 35,850. Term of patent 14 years.

To all whom it may concern:

Be it known that I, LOUIS A. PHILLIPS, a citizen of the United States, residing at Dobbs Ferry, in the county of Westchester and State of New York, have invented a new, original, and ornamental Design for a Sprinkler Nozzle, of which the following is a specification.

The figure is a perspective view of a sprinkler nozzle showing my new design.

I claim:

The ornamental design for a sprinkler nozzle, as shown.

In testimony whereof I affix my signature.

LOUIS A. PHILLIPS.
